CLAIM

The ornamental design for a retractable modem cable & case, as shown and described.

DESCRIPTION

FIG. 1 is a front and right side perspective view of a retractable modem cable and case showing our new design with one end of the cable partially extended;
FIG. 2 is a right side elevational view thereof;
FIG. 3 is a rear elevational view thereof shown with the both ends of the cable fully retracted; and,
FIG. 4 is a rear and right side perspective view thereof shown with the both ends of the cable partially extended. The left side and bottom are plane.
